INVENTOR

Charles G. Wieland

BY *John H. Holachuk*
ATTORNEY

UNITED STATES PATENT OFFICE.

CHARLES G. WIELAND, OF NEW YORK, N. Y.

TELEPHONE DIAPHRAGM.

Application filed June 22, 1925. Serial No. 38,691.

This invention relates to diaphragms such as are used in telephone receivers. The present invention being a further development of my invention for which I have filed 5 an application for Letters Patent on April 4, 1924, Serial No. 704,131.

As is known, the reproduction of the voice, or of sounds generally, in the telephone receiver is due to the vibration of 10 a thin sheet or disk of iron which is placed adjacent the two ends of the usual horseshoe magnet, the disk being secured at its edges only so that it may be free to vibrate. The strength of the sound produced depends 15 on the strength of the magnetic field around the poles of the magnet, the stronger the magnetic field the stronger the sound, and it is the purpose of the present invention to provide a construction which presents a magnetic field of increased strength, and which 20 will better utilize the strength of the magnet. To strengthen the magnetic field it is necessary to put a larger mass of magnetic material such as iron opposite the poles of 25 the magnet, and to do this I make use of a diaphragm presenting an increased amount 30 of material at its center in form of a boss or bosses along the two ends of the usual horseshoe magnet, to produce a magnetic field of increased strength while at the same 35 time preserving the essential flexibility of the diaphragm on the outer or marginal portion thereof.

Another object of the invention is the provision of novel and improved securing means 40 for attaching the diaphragm to the receiver cup and shell in order to positively avoid any accidental displacement of the same.

A still further object of the invention is 45 the provision of a diaphragm having a recess formed on one part of its margin to create lips adapted to engage the shell of the receiver and having a nail hole at a diametrically opposite part for allowing a nail to be driven through the same into the receiver cup for positively securing said diaphragm against accidental displacement.

For further comprehension of the invention, and of the objects and advantages 50 thereof, reference will be had to the following description and accompanying drawing, and to the appended claims in which the various features of the invention are more particularly set forth.

55 In the accompanying drawing forming a material part of this disclosure:

Fig. 1 is a face view of a diaphragm for telephone receivers constructed according to my invention.

Fig. 2 is a section on line 2—2 of Figure 1. 60

Fig. 3 is a view similar to Figure 1, of a modified form of my invention.

Fig. 4 is a section on line 4—4 of Figure 3.

Fig. 5 is a section on line 5—5 of Figure 3. 65

In the form of the invention illustrated in Figures 1 and 2, the diaphragm consists of a metal disc 10 having in approximately its center part, either a boss 11 made integrally therewith on its upper face, or also in addition to boss 11 on its upper face, a boss 12 integral with the disc on the lower face thereof, both bosses being substantially located above the poles of the customary 70 horse-shoe magnet of the telephone receiver. 75

The diaphragm is free to vibrate as the disc surrounding the centrally located boss or bosses is flat and thin, and because the diaphragm is supported and held in position 80 near its periphery on two oppositely disposed points.

At one of these points it is provided with a hole 13 allowing the passage of a nail or the like, adapted to be driven into the edge of the telephone receiver cup, while at the point diametrically opposite to the nail hole, the diaphragm is provided with a recess 14 by cutting the material in the middle and bending the cut pieces down to form parallel depending lips 15, angularly disposed to the diaphragm and these lips depend and fit into the edge of the receiver shell so that the diaphragm will be held securely in its adjusted position and cannot be moved while 90 the cover for the receiver shell is screwed 95 into place.

In the modified form of my diaphragm for the telephone receivers, illustrated in Figures 3, 4, and 5, the diaphragm disc 16 has two bosses 17 and 18 formed therewith on the side facing the ends of the poles of the horse-shoe magnet, each boss oppositely disposed to one of said poles, or the disc 16 may be provided, as indicated in Figure 5, 100 on both sides with separate bosses 17 and 18 on its upper face, and 19, and 20 on its lower face, each two of said bosses 18 and 19, and 17 and 20 located above the ends of the poles of the horse-shoe magnet respectively. 105

It should be understood that the openings 110 13 and 14 in the edge of the disc are diamet-

rically opposite from each other and that by means of these openings the diaphragm is secured in place. As a result of securing the diaphragm at diametrically spaced points, the freedom of vibration of that portion of the diaphragm on each side of the diameter connecting these points is somewhat reduced. When an undivided boss is mounted on the disc at the portion thereof that is adjacent the common diameter which includes the fixed points, the vibratile properties of the disc are further impaired for the boss which is attached to the less vibratile area of the disc tends to stabilize the adjacent area. That is to say, that the boss by reason of its attachment to the more stable area tends to extend this less vibratile area. With the spaced boss shown in Figs. 3, 4, and 5, it should be understood that there is no such tendency particularly when the space between the bosses is in line with the common diameter of the two fixed points.

Also in this form of my invention the diaphragm is free to vibrate and is supported by a nail driven through hole 13 into the edge of the telephone receiver cup while at a diametrically oppositely disposed point the diaphragm has a recess formed therewith by cutting the material and bending the two parallel lips 15 formed by the cut downwardly to fit into the edge of the receiver shell.

It will be clear that the boss or bosses are thus kept in line and parallel with the poles of the horse-shoe magnet, so that any loss of magnetic force is positively avoided. It is very important that these bosses be in straight line and parallel with the horse-shoe magnet, otherwise there would be a loss of magnetic power. To avoid this loss and keep this diaphragm firm, while screwing on the cover of the receiver shell, a little nail

is driven in the edge of the cup projecting thru the hole in the diaphragm, while on the other side of the cup a recess in the edge of the cup is provided.

It will be clear and understood that while I have shown and described as an example the preferred embodiments of my diaphragm, such changes may be made in the construction and arrangement of the bosses etc. as fall within the scope of the appended claims, without departure from the principle of my invention.

Having thus described my invention, what I claim as new and desire to secure by Letters Patent, is:

1. A diaphragm for telephone receivers comprising a disc, having an aperture and a projection at diametrically opposite points adjacent the periphery thereof, for adapting said disc to be secured to a receiver, and spaced apart bosses made integral with said disc and extending in spaced relation to each other, and longitudinally parallel to the diameter of said disc determined by said aperture and projection.

2. A diaphragm for telephone receivers comprising a disc having an aperture adjacent the edge thereof, for adapting said disc to be secured to a receiver, a downwardly directed projection on the edge of said disc diametrically opposite from said aperture for adapting said disc to be secured to said receiver at a point diametrically opposite from said aperture, and bosses made integral with said disc and spaced apart from the central portion thereof and from the diameter thereof determined by said projection and aperture.

In testimony whereof I have affixed my signature.

CHARLES G. WIELAND.
